ATTORNEY

UNITED STATES PATENT OFFICE

EDWARD J. KUNKELY, OF BRONX, NEW YORK

SHAKER BAG CAP AND FASTENER

Application filed April 14, 1931. Serial No. 529,998.

This invention relates to new and useful improvements in a shaker bag cap and fastener.

In various recovery systems shaker bags are used which are placed through man-holes into tanks and into which dust, pigments, etc. are filtered.

It is an object of this invention to construct a shaker bag cap and fastener which is characterized by a rigid member placed beneath the closed head of a shaker bag, a second rigid member above the head of the shaker bag, and means to clamp the members together whereby the shaker bag is held in an opened position and may conveniently be thus suspended.

A still further object of this invention is the provision of the rigid members in the form of discs for engaging in shaker bags which are circular in transverse cross section.

This invention has for a still further object the provision of a hand member attached upon the top of the rigid member for engaging some supporting element to accomplish supporting of the shaker bag.

Another one of the objects of this invention is the provision of a fastener arranged upon the top rigid member and operable with one hand so that the shaker bag may be lifted and held in place with the use of one hand only.

This invention has for a still further object the provision of a fastener for a shaker bag which is characterized by a perpendicular portion having a head portion extended directly over a peg for engagement in an aperture of a gridiron or support, bearings connected with the perpendicular portion to limit possible swinging of the bag, and a spring coacting with the bag to hold the fastener in place when engaged upon the gridiron.

This invention has for a still further object the provision of a means for moving the head portion and the peg of the fastening means so that it may be released with one hand.

A still further object of this invention is the construction of a shaker bag and fastener which is of simple durable construction,

dependable in use and efficient in action, and which can be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a side elevational view of a shaker bag with a cap and fastener constructed according to this invention.

Fig. 2 is a fragmentary sectional view taken on the line 2—2 of Fig. 1.

Fig. 3 is a fragmentary sectional view taken on the line 3—3 of Fig. 1.

Fig. 4 is a fragmentary sectional view of the top portion of a shaker bag provided with a cap and with a fastener constructed according to a modification of this invention.

Fig. 5 is a sectional view taken on the line 5—5 of Fig. 4.

Fig. 6 is a plan view of Fig. 5 shown without the gridiron.

Fig. 7 is a view similar to Fig. 5, but illustrating a modification, and

Fig. 8 is a fragmentary elevational view looking in the direction of the line 8—8 of Fig. 7.

The shaker bag cap and fastener according to this invention comprises a rigid member 10 located beneath the closed head 11 of a shaker bag 12. A second rigid member 13 is located above the head 11, and a means is provided for clamping these rigid members firmly together so as to hold the shaker bag in an opened position. The means referred to comprises a bolt 14 engaged through the rigid members and provided with a clamping nut 15.

As shown on the drawing, the shaker bag 12 is of circular construction in transverse cross section. A plurality of ring shaped rims 16 are attached upon the circumference of the bag so as to hold it open when suspended. The rigid members 10 and 13 are of disc form when the transverse cross section of

the bag is circular. The bolt 14 is provided with an eye element 17 at its top end to allow for the suspension of the bag.

In the modified form of the device illustrated in Figs. 4, 5 and 6, another embodiment of a fastening means has been disclosed for supporting the bag. This fastening means is in the form of a bracket consisting of a perpendicular portion 18 having a horizontal projecting head portion 19. A base portion 20 connects with the lower end of the perpendicular portion and is formed with a plurality of bearing surfaces 21 to limit possible swinging of the suspended bag upon a gridiron 22 which is provided with an aperture 23 through which a peg 24 engages. The peg 24 projects from the perpendicular portion 18. A plurality of bolts 25 engage through the bearing surfaces 21 and the rigid members 10 and 13 and serve to hold the fastening means upon the rigid members, and the rigid members in place upon the bag.

A spring 26 is attached at its bottom end by a screw 25 upon a portion of the base 20 of the fastener bracket. This spring is curved and acts against the outer end of the peg 24 and the edge of the head portion 19. The spring 26 is of a length so that its top end 27 projects slightly above the top face 30 of the head portion 19. The aperture 23 is of such a size as to be smaller than the width of the head portion 19 so that when the shaker bag is moved upwards against the stationary gridiron 22 and pries in between the spring 27 and the head portion 19, the head portion cannot engage through the opening 23. Consequently, it is necessary that the shaker bag be lifted up through the proper distance until the peg 24 engages through the aperture 23 in the gridiron. The shaker bag is now properly supported and cannot swing in that the surfaces 21 together with the head portion 19 act as limits.

In the modified form of the device illustrated in Figs. 7 and 8, a means has been disclosed for moving the head portion 19 and the peg 24 out from engagement with the gridiron 22. This means is in the form of a bar 28 hingedly mounted at 29, its bottom end, upon the back of the vertical portion 18. The coaxial spring 30 is arranged upon a hinge point and acts between the bar 28 and the perpendicular portion 18 for normally urging the bar against the perpendicular portion. The head portion 19 is integral with the bar 28, and so is the peg 24. The peg engages through an opening 31 formed in the perpendicular member 18 so as to extend to the front. To remove a shaker bag suspended by this fastener, it is merely necessary to move the head portion 19 laterally and counterclockwise relative to Fig. 7, so that the head portion 19 and the peg 24 are simultaneously moved away from the gridiron 22.

The shaker bag is then free from the gridiron.

While I have illustrated and described my invention with some degree of particularity, I realize that in practice various alterations therein may be made. I therefore reserve the right and privilege of changing the form of the details of construction or otherwise altering the arrangement of the correlated parts without departing from the spirit or the scope of the appended claims.

Having thus described my invention, what I claim as new, and desire to secure by United States Letters Patent is:—

1. A shaker bag, comprising a bag having a closed head, rigid members on opposite sides of said head, means for clamping the rigid members together, and means for supporting the rigid members upon some support comprising a fastener consisting of a vertical portion having a head portion, a base portion projecting from the bottom of the vertical portion and attached upon the top of the rigid members, a peg projecting from the vertical portion for engaging in an aperture of a gridiron and located below said head portion so that the top edge of the gridiron may engage the head portion to hold the shaker bag against swinging, and a spring attached upon the base portion and extending over the peg and the head portion.

2. A shaker bag, comprising a bag having a closed head, rigid members on opposite sides of said head, means for clamping the rigid members together, and means for supporting the rigid members upon some support comprising a fastener consisting of a vertical portion having a head portion, a base portion projecting from the bottom of the vertical portion and attached upon the top of the rigid members, a peg projecting from the vertical portion for engaging in an aperture of a gridiron, and a spring attached upon the base portion and extending over the peg and the head portion, bearing surfaces being arranged upon said base portion for acting against the bottom of said gridiron so that the head portion may act against the top of the gridiron and limit possible swinging of the bag.

3. A shaker bag, comprising a bag having a closed head, rigid members on opposite sides of said head, means for clamping the rigid members together, means for supporting the rigid members upon some support comprising a fastener consisting of a vertical portion having a head portion, a base portion projecting from the bottom of the vertical portion and attached upon the top of the rigid members, a peg projecting from the vertical portion for engaging in an aperture of a gridiron, and a spring attached upon the base portion and extending over the peg and the head portion, the vertical portion being movable with regards to the base portion so that

the head portion and peg may be retracted to release the bag.

4. A shaker bag, comprising a bag having a closed head, rigid members on opposite sides of said head, means for clamping the rigid members together, means for supporting the rigid members upon some support comprising a fastener consisting of a vertical portion, a head portion, a base portion projecting from the bottom of the vertical portion and attached upon the top of the rigid members, a peg for engaging in an aperture of a gridiron, a spring attached upon the base portion and extending over the peg and the head portion, and means for retracting the head portion and the peg so as to release the shaker bag from the gridiron comprising a bar pivotally mounted and normally urged against the rear side of the vertical portion, and said head portion and peg portion being connected on said bar.

Signed at New York, in the county of New York and State of N. Y. this 8th day of April A. D. 1931.

EDWARD J. KUNKELY.
